(57) **CLAIM**

The ornamental design for a disc cartridge, as shown and described.

DESCRIPTION

FIG. 1 is a front, top and right side perspective view of one embodiment of a disc cartridge showing our new design on an enlarged scale;

FIG. 2 is a front elevational view of the one embodiment;

FIG. 3 is a top plan view of the one embodiment;

FIG. 4 is a bottom plan view of the one embodiment;

FIG. 5 is a rear view of the one embodiment;

FIG. 6 is a left side elevational view of the one embodiment;

FIG. 7 is a right side elevational view of the one embodiment;

FIG. 8 is a front, top and right side perspective view of another embodiment of a disc cartridge showing our new design on an enlarged scale;

FIG. 9 is a front elevational view of the another embodiment;

FIG. 10 is a top plan view of the another embodiment;

FIG. 11 is a bottom plan view of the another embodiment;

FIG. 12 is a rear view of the another embodiment;

FIG. 13 is a left side elevational view of the another embodiment; and,

FIG. 14 is a right side elevational view of the another embodiment.
